UNITED STATES PATENT OFFICE.

EDWARD W. BELLAMY, OF TORRINGTON, CONNECTICUT.

PERMUTATION-PADLOCK.

1,397,717.

Specification of Letters Patent.

Patented Nov. 22, 1921.

Application filed January 29, 1920. Serial No. 354,917.

To all whom it may concern:

Be it known that I, EDWARD W. BELLAMY, a citizen of the United States, residing in the city of Torrington, county of Litchfield, 5 and State of Connecticut, have invented new and useful Improvements in Permutation-Padlocks, of which the following is a specification, reference being had to the accompanying drawings.

10 The present invention pertains to permutation padlocks.

The primary object is to produce a combination padlock in a simple, efficient and durable form, constructed of relatively few 15 parts and without springs or other elements likely to get out of order.

A further object is to produce a lock of this character having a central core, surrounded by a plurality of permutation rings, 20 said rings being channeled around their inner peripheries and slotted vertically to accommodate the lugs of the lock shackle.

A further object is to produce a lock of this kind, the permutation rings of which 25 carry characters in the way of letters and numbers, and which rings may be rotated so as to bring certain characters into vertical alinement, for the purpose of releasing the shackle from the lock.

30 In the drawings:

Figure 1 is a perspective view with a section broken away to reveal the inner construction of the lock, the lock being shown in open position.

35 Fig. 2 is a similar view showing the lock closed.

Fig. 3 is a detail of the shackle.

Fig. 4 is a detail of the top cap.

Fig. 5 is a detail of the base and core.

40 Fig. 6 is a detail of one of the permutation rings.

In carrying out my invention in its preferred construction, I provide a cylindrical core 1, carrying the circular base 2, the 45 core being disposed centrally relative to said base. The core 1 is provided with vertical channels 3 and 4, same being located diametrically opposite one to the other. The core 1 is likewise pierced with the vertical threaded bore 5 at its central point. The channels 3 and 4 are extended downwardly into the base 2 and enlarged, thus forming the cups 3' and 4', the purpose whereof will later appear. The circular cap 55 6 carries the integrally, centrally formed, threaded bolt 7, adapted to mesh with the threaded bore 5 aforesaid, formed in the core 1. The cap 6 is of the same diameter as the base 2, and by means of the threaded bolt 7 may be securely screwed down into place upon the top of the core 1. When so located, a set screw 8 mounted through the cap 6 and engaging the core 1, serves to lock the cap securely in position and prevent its accidentally rotating and becoming unloosened. The cap 6 is pierced with two shackle holes 9 and 10, adapted to fall into alinement with the channels 3 and 4 formed upon the core 1, as aforesaid. One of the shackle holes, as 10, is countersunk at 60 its under side, as shown, to accommodate the foot of one of the shackle arms, as will later appear. A plurality of permutation rings 11 are provided, and adapted to slidely engage the core 1, being seated thereover. A number of these rings, as for instance 4 of them, may thus be mounted over the core 1 between the cap and base. These rings are provided with vertical slots 12 and 13 to correspond to and offset the vertical 65 channels 3 and 4 formed in the core 1. These slots 12 and 13, in coöperation with the channels 3 and 4 are adapted to engage the shackle of the lock as will be later described. The permutation rings 11 are likewise each formed with a central annular channel 14 around its inner periphery, adapted to engage the lock lugs of the shackle arms for locking same. A U-shaped shackle 15 is provided, the arms 16 and 17 70 thereof having outwardly projecting lock lugs 18 and 19, said lugs being so formed, shaped and spaced that while the inner edges of the shackle 15 pass down the channels 3 and 4 of the core 1, the lugs 18 and 19 will pass down the slots 12 and 13 of the 75 permutation rings 11 while the lugs 18 and 19 slidingly engage the channels 14 of the rings 11; thus the rings 11 may readily be rotated over the lugs 18 and 19 of the shackle 15, for the purpose of locking the shackle in place. Any desired series of characters may be cut or inscribed around the outer peripheries of the rings 11, and 80 guide lines 20 may be cut upon the outer faces of the cap and base, and adapted to register with the similar divisional or guide lines 21 cut upon the permutation rings 11 in combination with the characters, as 85 shown. The guide lines 20 are preferably 90 95 100 105 110

cut exactly opposite the channels 3 and 4 of the core 1 while the guide lines 21 are cut exactly opposite the slots 12 and 13 of the rings 11; thus by turning the rings 11 so that the slots 12 and 13 upon each respective ring fall into vertical alinement, it is evident that the lugs 18 and 19 will be free to pass downwardly or upwardly for the purpose of locking or unlocking the shackle 15 from the body of the lock. The lower end of the arm 17 of the shackle 15 is extended below the lower end 23 of the arm 16 and is provided with an extended foot 22 which is adapted to engage the counterbore formed at the lower side of the shackle hole 10, thus retaining the shackle permanently in place upon the lock while permitting the shackle to swing freely, for the purpose of opening the lock. When the shackle 15 is closed down into the lock the foot 22 of the arm 17 is received by the cup 4', formed in the base 2, whereby the rings 11 are not interfered with and are enabled to rotate freely over the lugs 18 and 19. In order to facilitate assembling, the lug 22 may be formed at the end of the stem 24, said stem being adapted to engage a bore 25 in the arm 17 and being locked therein by means of a set screw 26.

30 The parts of course are all to be rightly and nicely proportioned and finished to meet practical requirements. The permutation rings 11 are all exactly similar and thus interchangeable, and by providing additional or extra rings 11, and carrying the characters located adjacent the guide lines 21, in different ones of the rings, the combinations required to open the lock may readily be changed by changing the rings.

35 40 To change the rings and thus the combination, it is only necessary to remove the cap 6.

45 While I have herein described a certain specific method of constructing and assembling the elements of my invention, it is understood same may be varied in minor details, not departing from the spirit of my invention as defined in the appended claims.

50 What I claim to be new and patentable is:

50 1. A permutation padlock comprising a circular base; a cylindrical core centrally extended from the base; two channels cut along the core, upon diametrically opposite sides thereof and perpendicularly to the base, said channels being extended into the base in the form of enlarged cups; a central, threaded bore extended down into the top of said core; a circular cap, corresponding to the base; a threaded bolt centrally extended from the cap, and adapted to screw into the threaded bore of the core; two shackle holes pierced through said cap, upon diametrically opposite sides thereof, and adapted to register with the channels cut along said core, one of said holes being countersunk at its under side; a U-shaped shackle, having its arms adapted to enter the shackle holes formed through the cap and to travel the channels formed along the core, the lower end of one arm having an extended foot adapted to engage the countersunk shackle hole in the cap, as means for linking the shackle to the lock, and the lower ends of both arms being adapted to seat into the cups formed in the base as aforesaid; a plurality of outstanding lock-lugs formed along each shackle arm; a plurality of similar, interchangeable permutation rings, rotatively mounted over the core, so as to fill the space between the cap and base; an annular channel cut around the inner periphery of each permutation ring, each channel being adapted to slidingly engage the opposite lock-lugs upon the shackle arms and thus lock the shackle in place; two transverse slots cut across the inner periphery of each permutation ring and across its annular channel, upon diametrically opposite sides, the respective slots of the several rings being adapted to register as the rings are rotated and thus release the lock-lugs of the shackle; and guide lines and permutation characters formed upon the outer faces of the cap, base and rings to facilitate the formation of combinations.

55 60 65

65 70 75 80 85 90 95 100 105 110 115 120 125 130

countersunk at its under side; a set screw mounted through the cap and seated in the core as means for locking the cap in place; a U-shaped shackle, having its arms adapted to enter the shackle holes formed through the cap and to travel the channels formed along the core, the lower end of one arm having an extended foot adapted to engage the countersunk shackle hole in the cap, as means for linking the shackle to the lock, and the lower ends of both arms being adapted to seat into the cups formed in the base as aforesaid; a plurality of outstanding lock-lugs formed along each shackle arm; a plurality of similar, interchangeable permutation rings, rotatively mounted over the core, so as to fill the space between the cap and base; an annular channel cut around the inner periphery of each permutation ring, each channel being adapted to slidingly engage the opposite lock-lugs upon the shackle arms and thus lock the shackle in place; two transverse slots cut across the inner periphery of each permutation ring and across its annular channel, upon diametrically opposite sides, the respective slots of the several rings being adapted to register as the rings are rotated and thus release the lock-lugs of the shackle; and guide lines and permutation characters formed upon the outer faces of the cap, base and rings to facilitate the formation of combinations.

2. A permutation padlock comprising a circular base; a cylindrical core centrally extended from the base; two channels cut along the core, upon diametrically opposite sides thereof and perpendicularly to the base, said channels being extended into the base in the form of enlarged cups; a central, threaded bore extended down into the top of said core; a circular cap, corresponding to the base; a threaded bolt centrally extended from the cap, and adapted to screw into the threaded bore of the core; two shackle holes pierced through said cap, upon diametrically opposite sides thereof, and adapted to register with the channels cut along said core, one of said holes being countersunk at its under side; a U-shaped shackle, having its arms adapted to enter the shackle holes formed through the cap and to travel the channels formed along the core, the lower end of one arm having an extended foot adapted to engage the countersunk shackle hole in the cap, as means for linking the shackle to the lock, and the lower ends of both arms being adapted to seat into the cups formed in the base as aforesaid; a plurality of outstanding lock-lugs formed along each shackle arm; a plurality of similar, interchangeable permutation rings, rotatively mounted over the core, so as to fill the space between the cap and base; an annular channel cut around the inner periphery of each permutation ring, each channel being adapted to slidingly engage the opposite lock-lugs upon the shackle arms and thus lock the shackle in place; two transverse slots cut across the inner periphery of each permutation ring and across its annular channel, upon diametrically opposite sides, the respective slots of the several rings being adapted to register as the rings are rotated and thus release the lock-lugs of the shackle; and guide lines and permutation characters formed upon the outer faces of the cap, base and rings to facilitate the formation of combinations.

ed to slidingly engage the opposite lock-lugs upon the shackle arms and thus lock the shackle in place; and two transverse slots cut across the inner periphery of each permutation ring and across its annular channel, upon diametrically opposite sides, the respective slots of the several rings being

adapted to register as the rings are rotated and thus release the lock-lugs of the shackle.

EDWARD W. BELLAMY.
